BENDING OF WOOD

Karl Michaëlis, The Hague, Netherlands

Application October 8, 1937, Serial No. 168,035
In Germany October 15, 1936

7 Claims. (Cl. 144—309)

This invention relates to the bending of wood, and more particularly to novel processes and machinery for dry-bending wood panels and the like.

It is an object of this invention to provide methods and devices for dry bending, i. e. for bending without previous boiling or steaming, wood panels and the like, including blanks of considerable thickness.

It is another object of this invention to provide methods and devices whereby to dry-bend wood panels and the like in a small fraction of the time involved in prior procedures and at correspondingly low expense.

Other objects, and the manner in which they are attained, will appear from the following description.

In the prior art it has been customary to bend wood by first subjecting it to a thorough boiling or steaming treatment whereby to thoroughly impregnate it with moisture, thereafter molding the wet blank, mostly under pressure, and finally drying the bent shape by storing each piece over an extended period of time, frequently not less than 48 hours, in individual molds or clamps. Evidently, this procedure is time-consuming and requires costly installations, a great number of molds and considerable storage space, apart from the fact that the physical and chemical properties of the wood undergo material changes in consequence 30 of the lixiviation with hot water or steam. In view of all these disadvantages, there had been frequent attempts at providing methods and apparatus for dry-bending wood, all of which are however, only applicable in certain specific cases 35 and are moreover limited to comparatively thin stock.

The present invention utilizes in a novel manner the circumstance that dry wood, when heated, is rendered temporarily compressible and in that 40 state can be molded. According to the invention I first heat uniformly the inner side, i. e. that side which in the bending operation becomes the concave side, of substantially the entire panel part to be bent so as to build up in this panel part a 45 temperature gradient with the higher temperature on the inner side of this part whereby to render the wood on this inner side compressible. When the panel part has become pliable as a whole, I bend it while its inner side still retains 50 substantially the temperature imparted to it, thereby preventing any appreciable loss of heat which might result in a diminution of pliability.

In the preheating of the wood I use a flat surface heater, i. e. a source of heat capable of uniformly and at once distributing over the entire

area of a flat panel part of considerable length and width—as distinguished from heat sources having substantially only a spot or line heating effect—an amount of heat sufficient to render the wood compressible.

In order to avoid heat losses on the inner side of the panel, to which the heat is applied, I prefer arranging the heat source so closely adjacent to the mold or bending device as to prevent cold air from coming in contact with the inner side of the 10 panel before and during the bending. To this end, in a preferred embodiment of my invention I arrange the heat source tangentially and close to the curved mold surface and pull the panel away from this heat source in constant sliding 15 contact with it and around and into parallel relation to the curved mold surface, which is preferably heated also.

In order to avoid friction between the wood and the mold and to facilitate the operation, the 20 mold may be supported for rotation by means of a crank, a weighted lever, a spring under tension, a motor of some kind or by other means, and, when thus rotated, will wind up the heated panel.

Instead of thus pulling the sheet in order to 25 move it away from the heating device, I may impart to the mold, to which the heated panel is fixed, rolling motion relative to and in contact with the panel, thereby causing the heated side of the panel to apply itself to the curved mold 30 surface.

In this way I am enabled to bend large panels of considerable thickness without any appreciable risk of breakage of the outer layers. Curvatures of 100 mms. radius can easily be obtained with 35 8-10 mm. sheets; thinner sheets can of course be curved through smaller radii. If the panels are properly preheated, and if provision is made for feeding to the mold a fresh preheated sheet right after the curved panel is removed from the mold, 40 the bending process can be carried through at a quantity production rate.

Having thus explained the principle underlying my invention, I will now proceed to describe some 45 means of carrying same out on an industrial scale, having reference to the drawings affixed to this specification and forming part thereof which illustrate by way of example and in a purely diagrammatic manner some devices embodying my invention and adapted to produce curved shapes by bending panels of plain and plywood.

In the drawings
Fig. 1 shows in a purely diagrammatic manner the pulling of a preheated panel onto and around

a stationary curved mold, represented by way of example by a steel or copper cylinder.

Fig. 2 is a diagram showing a modified way of carrying out the same operation.

5 Fig. 3 illustrates in a similar manner the winding up of a preheated panel on the cylindrical surface of a mold arranged for rotation about its axis.

10 Fig. 4 illustrates another manner of winding up a preheated panel for the purpose of bending it.

15 Fig. 5 is an elevation of a bending machine embodying the principle of operation illustrated in Fig. 3, and

15 Fig. 6 is a similar view of another bending machine embodying the principle of operation illustrated in Fig. 4, while

20 Fig. 6a illustrates the machine of Fig. 6, however, with the parts shown in their end positions.

20 Fig. 7 is a partial end view of the machine, shown in Fig. 6, partly in section, and

Fig. 8 illustrates a detail.

Referring to the drawings and first to Fig. 1, 1 is a support for a mold cylinder 2 arranged for being heated in any suitable manner, for instance by means of electrical resistance wires or the like 2a. The uprights further support a preheating device, represented in the drawings by an electrical heating plate 3. Rollers 4 extending 25 across the heater 3 and spaced from its surface about the thickness of the panel to be bent serve to prevent the sheet, shown at 5, from being lifted off the heater. 6 is a gripper which is here shown in a conventional manner as gripping the edge portion of the panel; 7 is a chain fixed to the gripper and extending around part of the mold and 8 is a spring placed under tension by means of a pedal lever 9 and exerting on the gripper and the panel a pull sufficing to 30 force it into contact with the hot mold surface as soon as it is heated up to the extent of being prepared for bending. As soon as this stage has been reached, the panel of wood will be pulled around the mold and into contact with its surface and, in trying to follow the descending chain, will be curved at right angles to the horizontal part of the panel, the radius of curvature being determined by the radius of the mold.

55 The curved portion of the panel will substantially retain its curvature. With panels of a certain thickness a tendency, prevailing only as long as the panel is warm, of expanding again, can be counteracted by mounting the curved panels in suitable cages until they have cooled down, or by bending them somewhat farther than required.

Instead of pulling the panel by hand or by means of a spring of some sort, it may be carried or wound around the mold cylinder by an arm 60 rotated by a motor. This is shown in a conventional manner in Fig. 2, where 98 is the gripper arm fixed to a gear wheel 10 mounted on the mold axle at 11 and meshing with a pinion 12 secured on the shaft of an electromotor 13, 65 which drives the wheel 10 and arm 98 and causes the panel to be pulled off the heater plate and around the mold.

70 While in the two instances mentioned above the mold may be or is stationary, Fig. 3 illustrates a particularly efficient manner of bending panels, in which the mold is arranged for rotation about its axis, thus avoiding all friction between the panel and the mold and using the mold itself as a means for pulling and winding 75 up the preheated panel.

In Fig. 3 the mold 14 is mounted for rotation about its axis and an arm 15 carrying a weight 16 is fixed to its axle 17 and at 18 to the mold cylinder proper. The weight 16 has the tendency to drop under the influence of the gravity force, so as to turn the arm or lever 15 and correspondingly the mold 14 fixed to such arm. 19 represents a resistance heating the mold and 20 is some sort of gripping means fixed to the circumference of the mold. The panel 21 is held down on the electrical heater 22 by means of rollers 23 which may be adjusted vertically. If the panel is gripped and fixed to the mold with the arm 15 extending at a slight angle to the vertical, the mold will remain stationary since the tendency of the weight to drop so as to turn the mold will be insufficient to overcome the resistance offered by the wood, as long as the panel 21 is cold or not preheated to the extent of being pliable. Only when this point is reached, 20 the lever action of the weight will gradually overcome the resistance of the panel to a change of form and in slowly turning the mold in the direction of the arrow will pull the panel off the heater and will wind it up on the mold, as shown in dot and dash lines. Owing to the elasticity of the pull exerted on the sheet, provided that the weight and leverage are adapted to the wood thickness, no undue stress will be exerted on the outer layers of the wood and cracking and splitting, which might arise when forcing the panel onto the mold by a constant force, will be avoided with certainty.

25 This principle of operation is utilized in the bending machine illustrated in Fig. 5, wherein 24 is one of the standards, 25 is the mold cylinder, 26 is a gear keyed on the mold axle 27, 28 is a larger gear meshing with gear 26 and mounted to turn on an axle 29 in the standards. 30 is the weighted lever arm keyed on the axle 29, 31 is an auxiliary arm carrying a counterweight 32 and pivoted to the arm 30 near its pivot point. 33 is the gripper fixed to the mold cylinder, 34 is a roller holding the panel 35 down on the heater plate 36, and 37 are vertically movable 30 bearings for this roller. 38 is one of a pair of arms carrying weights 39 and holding between them another roller 40.

45 In the operation of this machine, if it is desired to bend the panel U-fashion, it is fixed to the mold cylinder by means of the gripper 33 at the point where the bend shall begin. On the panel being preheated to bending temperature, the action of the weighted lever arm 30 will pull the panel off the heater plate 36 and around the mold as shown in dot and dash lines. Owing to the insertion of a step-up gearing between the arm and the mold an angular displacement of the arm through an angle of 60° may cause the mold cylinder to rotate through an angle of 180° as is here required in order to bend the panel U-fashion.

50 The winding up of the panel of wood on a rotatory curved molding surface can also be effected in the manner illustrated diagrammatically in Fig. 4. Here, instead of shifting the panel relative to the heater and pulling it on the mold rotating in stationary bearings, the heater is shifted relative to the panel, the plane part of which remains stationary, and the mold is arranged to roll relative to and to wind up the preheated part of the panel. By thus arranging the coacting parts I am enabled to wind up and bend both ends of a panel simultaneously, either in the same or in opposite directions. As shown 55

in the diagram of Fig. 4, 41 and 42 are two shaping cylinders, one placed above, the other below the panel indicated at 91. 43 and 44 are heating plates arranged in contact with the panel in front of the cylinders 41 and 42, respectively. The heaters are pivoted, by means of links indicated at 45 and 46, respectively, to the axles 47 and 48, respectively, of their cylinders.

Assuming the panel to be gripped by the two cylinders at the points of contact 49, 50 and the portions of the wood in front of the cylinders to be preheated, the cylinders, if forced to roll relative to and in contact with the sheet, for instance by springs 90 gripping the cylinders, will wind it up and bend it as illustrated in dotted lines, the heaters being shifted relative to the panel as the cylinders go through their rolling movement.

This mode of operation is followed in the bending machine shown in Figs. 6-8, in which the two ends of a panel are bent simultaneously in opposite directions at about right angles to the middle portion of the panel. Weighted levers are again resorted to for supplying the bending force. 51 is the machine structure and 52, 53 are horizontal guideways formed thereon at different levels. 54, 55 are slide pieces forming bearings supporting the axial journals 56 and 57 of two semi-cylindrical shaping molds 58 and 59, respectively, which may be heated in any suitable manner. Arms 60, 61, carrying weights 62, are fixed on the mold journals, preferably one on either side of each mold. Between the mold ends and the slide pieces are keyed on the mold journals toothed wheels 63, 64 which mesh with racks 65, 66, respectively, secured on the structure 51 (Figs. 7 and 8). Evidently, when the weighted levers drop after the wood has been rendered sufficiently pliable to permit of rotary displacement of the molds, the aforementioned gear arrangement gives rise to a controlled longitudinal displacement of the molds; for example, as shown in Fig. 6, the molds 58 and 59 are caused to move in a direction toward each other. 67, 68 are the preheating plates carrying arms 69, 70, by means of which they are pivotally secured to the mold journals. The heater 67 rests on the panel to be bent, while the heater 68 is supported for sliding motion on the structure by means of laterally projecting pins 95.

50 The gripping device for holding the panel down on the mold 59 is shown in Fig. 7 as comprising two arms 74 pivoted to the levers 61 and holding between them a cross bar 75 on which is mounted a presser bar 76. The presser bar 76 is displaceably supported by spring-loaded pins 78, an eccentric 77 being provided for displacing the bar 76 against the pressure exerted by such springs.

55 In the operation of this device the panel 71 to be bent is fixed to the two molds by means of the gripping devices 72, 77, by inserting the panel between the mold and the presser bar cooperating therewith, and actuating the correlated eccentric so as to force the presser bar onto the panel to clamp the same firmly on the mold, and on the panel being preheated to bending temperature, the weighted levers will overcome its resistance to bending and will begin to move in the direction of the arrows, rotating the molds 70 which, when so rotated, are forced by the toothed wheel and rack gearings to roll relative to the sheet, their axles sliding, with their bearings 54, 55, in the horizontal guideways, in the direction toward each other, so as to reduce the distance 75 between the molds as required by the winding-up

operation thereof. In this rolling movement the molds shift their heaters 67, 68 in front of them in contact with the sheet. When the lever arms have swung through 90°, the molds have completed a quarter turn and have forced the ends of the panel to bend around into the position shown in Fig. 6a. By turning the top heater 67 into vertical position the S-shaped panel can be turned about its transverse middle line and lifted free of the molds, which are then returned into 10 their initial position.

When bending panels on a quantity basis, a number of panels may be arranged on juxtaposed heaters and heated up simultaneously. Evidently, the shifting of panels from one auxiliary pre-heating device to the adjacent one which is situated more closely to the main heating and bending station, or the shifting of panels to such station, as well as the supply of panels to that auxiliary preheating device which is most remote with respect to such main station, may be carried out manually or by any well known mechanical means. In this manner the rate of bending can be increased up to the period required for fixing in place, bending and removing 20 each fully preheated panel. The number of panels to be preheated depends on the period of time required to bend the panel on the mold.

With thin plywood panels, which can be heated up in a few seconds, this simultaneous preheating of a plurality of panels may of course be dispensed with.

The panels can also be wound up through more than 360° to form double-walled cylinders.

The preheating of the panels, which was described as being done with the aid of plate heaters, might as well be effected by means of hot gases or flexible heaters, as explained more fully in my copending applications for U. S. Patent Serial Nos. 173,574 and 253,111.

While in the examples here given circular and semi-circular shaping molds are used, it is obvious that molds or bending tools of non-circular and, more especially with thinner sheets, also polygonal surface and of irregular surface may 45 be applicable.

In the foregoing specification and the appended claims, the term "dry-bending" is intended to refer to the bending of inwardly dry panels, as distinguished from the bending of panels which have been rendered pliable by thorough impregnation with moisture, e. g. by boiling and/or steaming; and the term "wood panels" is intended to include all kinds of blanks, such as boards, strips and the like, composed of wood 55 fibres, including composite materials of wood and a binder, such as plywood.

Various changes may be made in the details disclosed in the foregoing specification without departing from the invention or sacrificing the 60 advantages thereof.

I claim:

1. The process of dry-bending wood panels and the like, which comprises preheating uniformly the inner side of substantially the entire part to 65 be bent of an inwardly dry panel so as to build up therein a temperature gradient with the higher temperature on the inner side of said part whereby to render the wood on said inner side compressible, and immediately thereafter and 70 while the wood on said inner side still retains substantially said temperature, bending the part thus preheated.

2. The process of dry-bending wood panels and the like, which comprises preheating uniformly 75

- the inner side of substantially the entire part to be bent of an inwardly dry panel so as to build up therein a temperature gradient with the higher temperature on the inner side of said part whereby to render the wood on said inner side compressible, and immediately thereafter and while the wood on said inner side still retains substantially said temperature, bending the part thus preheated by forcing said inner side into face to face contact with a hot molding surface.
3. The process of dry-bending wood panels and the like, which comprises preheating uniformly the inner side of substantially the entire part to be bent of an inwardly dry panel so as to build up therein a temperature gradient with the higher temperature on the inner side of said part whereby to render the wood on said inner side compressible, and immediately thereafter and while the wood on said inner side still retains substantially said temperature, bending the part thus preheated by pulling it around a hot molding surface.
- 25 4. A device for dry-bending wood panels and the like, comprising in combination, a flat-surface heater for heating one surface of part of a panel, a curved mold closely adjoining said heater, and means for bending the heated surface of the panel part into contact with said

mold, said surface to become the concave surface of the bent part.

5. A device for dry-bending wood panels and the like, comprising in combination, a flat-surface heater for heating one surface of part of a panel, a curved mold closely adjoining said heater and means for pulling the panel part heated by said heater away from said heater and around said mold with the heated surface becoming the concave surface of the bent part.

6. A device for dry-bending wood panels and the like, comprising in combination, a flat-surface heater for heating one surface of part of a panel, a curved mold closely adjoining said heater, means for pulling the panel part heated by said heater away from said heater and around said mold, and means for maintaining the panel part in contact with said heater while transferring it onto the mold.

7. A device for dry-bending wood panels and the like, comprising in combination, a curved mold supported for rotation, a flat-surface heater for heating one surface of part of a panel, said heater being supported in close tangential relation to the curved surface of said mold, means for fixing a panel to said curved mold surface, means for rotating said mold and means for holding the panel part in sliding contact with said heater.

KARL MICHAELIS.
